UNITED STATES PATENT OFFICE.

JOSEF BIERMANNS, OF KARLSHORST, NEAR BERLIN, GERMANY, ASSIGNOR TO GENERAL ELECTRIC COMPANY, A CORPORATION OF NEW YORK.

PROTECTIVE APPARATUS.

Application filed November 30, 1927, Serial No. 236,838, and in Germany December 31, 1926.

My invention relates to improvements in protective apparatus for electric systems and more particularly to improvements in protective apparatus of the type wherein selectivity is dependent on the distance between the protective apparatus and the fault. An object of my invention is to provide improved protective apparatus whereby to obtain a high degree of selectivity and yet quickly to effect the disconnection of a faulty portion of an electric circuit.

My invention will be better understood from the following description when considered in connection with the accompanying drawing and its scope will be pointed out in the appended claims.

In the accompanying drawings, Fig. 1 illustrates, partly in diagram and partly in perspective, protective apparatus embodying my invention; Figs. 2 to 5 inclusive are diagrams explanatory of my invention; and Figs. 6 and 7 represent diagrammatically modifications of my invention.

In relays of the so-called distance type, the time of operation is dependent on the distance between the relay and the fault. If a fault such as a short-circuit occurs near the relay, then it will operate in a very short time which may be called the minimum or fundamental time. The farther the fault is from the relay, the greater the time of operation. As shown in Fig. 2, this time may be for example, substantially in accordance with the straight line ON which represents the dependence on the position of the fault of the time of operation of the relay Ra located in the station a. The relay Ra normally has only the line section ab to protect and the relay Rb at the station b is relied upon to protect the section bc. In case of a short-circuit near station b, the time of operation of the relay Ra is considerably greater than the minimum time. In such cases damage to the system loaded with the excess current may occur under certain circumstances.

Now, instead of having the time of operation of the relay increase with the distance between the relay and the fault for the section to be protected by the relay, a relay whose time of operation is substantially constant for faults anywhere on the protected section and increases only for faults outside of the section would satisfy requirements as to selectivity. The characteristic of such a relay Ra would be substantially as shown in Fig.

3 in which OM is horizontal from station a to station b and MN from station b to station c has a slope similar to ON of Fig. 1. Since, however, the time of operation of the relay Ra in case of a short circuit near station b in the line section bc would be only slightly greater than the minimum time of the relay Rb which is to be chosen as great as the minimum time of the relay Ra, the time difference is not sufficient and both relays may operate thus effecting the disconnection of not only the faulty section but also a sound section. This disadvantage may be overcome by a relay having the characteristic OM'N shown in Fig. 4. In this case, the constant time of operation ceases at the point M' which must be far enough from the station b to insure the necessary time difference. Also the relay may have the characteristic shown in Fig. 5. In this case, the minimum time is maintained throughout the section ab but for faults outside this section the time of operation increases suddenly from OM to N'N.

In the embodiment of my invention shown in Fig. 1, an electric circuit 10 is arranged to be controlled by suitable interrupting means such as a circuit breaker 11 which is arranged to be controlled by relay means Ra of the so-called distance type. The particular relay means chosen for the illustration of my invention is a modification of the relay disclosed in my United States Letters Patent 1,527,623 issued February 24, 1925, to the assignee of this invention. This relay comprises two independent relatively movable cooperating members such as contacts 12, 13 which, as shown, are arranged to control the circuit of the circuit breaker trip coil 9.

On the occurrence of a fault on the circuit 10, the contact 12 is arranged to be rotated against the bias of a spring 14 in the direction indicated by the arrow 15 at a speed dependent on the circuit current through suitable electromagnetic means comprising an induction disc 16 and magnetic elements 17 and 18, the latter of which is provided with windings 19, 20 connected to be energized in accordance with the circuit current through a current transformer 21. On the occurrence of a fault on the circuit 10 with a predetermined direction of power, the contact 13 is arranged to be rotated against the bias of a spring 22 in the direction indicated by the arrow 23 to a position dependent on

a voltage of the circuit 10 through suitable electromagnetic means comprising an induction disc 24 and magnetic elements 25 and 26, the latter of which is provided with windings 27, 28 respectively connected to be energized in accordance with the circuit current and a circuit voltage through the current and potential transformers 21 and 29 respectively. As pointed out in my Letters Patent 1,527,623 the magnetic element 26 has its central leg, which carries the current winding 27, arranged to saturate at the minimum overcurrent for which operation is desired. Consequently, while the direction of movement of the disc 24 is dependent on the direction of power, the magnitude of the torque exerted on the disc 24 by the windings 27 and 28 is such as move the disc at a speed dependent and therefore to position the same in accordance with the circuit voltage. When the direction of power is such as to move the disc 24 oppositely to the direction indicated by the arrow 23, the voltage contact 13 moves a stop 30 into the path of movement of the contact 12 thus preventing contact engagement. When the direction of power is such as to move the disc 24 in the direction indicated by the arrow 23, the voltage contact 13 will take a position to which it will be followed by the current contact 12 and overtaken in a time dependent on the distance between the relay and the fault.

In Fig. 1, the positions of the parts are those normally occupied, the electromagnets 35 exerting no torques on the discs 16, 24 since their windings 20, 28 are normally open-circuited and become energized only on the occurrence of a current sufficient to attract the magnetic element 17 to close its contacts 31 and 32. In case of a short-circuit in the immediate vicinity of the relay, the voltage completely disappears and consequently the disc 24 does not move. Therefore the time required by the contact 12 to overtake the contact 13 is the minimum time of operation of the relay. If the increasing voltage which occurs at the relay location with increase in the distance of the fault that is as the faults occur in the section *ab* farther and farther from station *a*, were dependent only on the distance between the relay and the fault point, then it would be necessary only to give the spring 22 a constant preliminary tension corresponding to the voltage drop from *a* to *M'* so that all faults between these points will be disconnected in the minimum time.

However, inasmuch as the voltage drop is dependent on the value of the short-circuit current, I propose in accordance with my invention to influence the voltage contact 13 by an effect dependent on the difference between the voltage and the current. This may be done, as shown in Fig. 1, by making the counter torque, that is the torque of the spring 22, determining the position of the

disc 24 dependent upon the circuit current. For this purpose the outer end of the spring 22 is not secured to a fixed point but to a point whose position is varied in accordance with the intensity of the current. As shown in Fig. 1, this is done by securing the outer end of the spring 22 to one end of a lever 33 pivoted at 34. The other end of the lever 33 is connected to the armature of an electromagnet 35 which is arranged to be energized in accordance with the circuit current so as to increase the tension on the spring 22 as the armature is pulled into its winding against the action of a spring 36 whose tension may be adjusted in any suitable manner. A predetermined position of the armature of the electromagnet 35 corresponds to some value of current for which the spring 22 has a predetermined preliminary tension. The point *M'* may, therefore, be shifted as desired. The other end of the spring 22 is not fixed to the disc 24 but in the normal or rest position of the disc abuts a fixed stop 37 from which it is moved through the projection 38 on the disc shaft only when the disc moves in the direction indicated by the arrow 23. The disc 24 in its rest position is, therefore, not under the influence of the spring 22 and can turn freely in the opposite direction to actuate the stop 30.

My invention is not limited to relay means such as shown in Fig. 1 but can be arranged in any suitable manner so that an effect in accordance with the current is caused to oppose the effect exerted by the voltage in conjunction with the biasing means on the time of operation. Thus, for example as shown in Fig. 6, a voltage drop produced by a current proportional to the circuit current and flowing through a resistance 39 in circuit with the current transformer 21 can be so arranged as to oppose the effect of the voltage in the winding 28. A spring 22' provides the necessary counter torque for the disc 24. In this Fig. 6 only that portion of the relay *Ra* whose structure is altered is shown. It will be understood that the remainder of the structure can be according to Fig. 1.

In order to obtain the step arrangement characteristic shown in Fig. 5, I provide as shown in Fig. 7 in conjunction with the relay *Ra* of which only the voltage element is shown for simplicity, a relay 40 which is operative on the occurrence of a fault in a predetermined portion of the circuit such as a section *bc* to the right of section *ab* to eliminate the effect of the current in the actuating means of the voltage contact. While any suitable relay may be employed, I have chosen for illustration a relay of the directional distance type such as disclosed in the copending application of Otto Mayr for circuit protection, Serial No. 92,093, filed March 3, 1926, and assigned to the same assignee as this invention. As shown this relay is of the induc-

tion disc type having a disc 41 and electro-magnetic actuating means therefor comprising windings 42, 43, 44 which are connected and arranged to exert an effect proportional to a voltage of the circuit and the difference between the circuit current and a current proportional to a potential of the circuit and inversely proportional to a characteristic of the impedance of a portion of the circuit such as the section *ab*. The winding 42 is connected to be energized in accordance with a potential of the circuit and cooperates with the windings 43 and 44 which work in opposition. The winding 43 is connected to be energized in accordance with the circuit current and the winding 44 is connected in series with an impedance device 45 across the secondary of the potential transformer 29. This impedance device is proportioned to have an impedance characteristic proportional to an impedance characteristic of the section *ab*. The operation of this relay is such that for a fault outside of the section *ab*, the disc 41 will be moved in one direction and for a fault in the section *ab* in the opposite direction. Then under normal conditions and for a fault on the section *ab* the relay 40 will maintain its contacts 46 closed and the circuit of the electromagnet 35 of the relay *Ra* energized. If, however, a fault occurs outside the section *ab* as for example in the section *bc* to the right, the torque on the disc 41 will reverse thus opening the contacts 46 and removing the control of the electromagnet 35 from the voltage contact 13 of the relay *Ra*. The spring 36 then holds the lever 33 against a stop 47 which may be adjustable. There will then be a definite tension in the spring 22 such that for faults to the right of the station *b*, the time characteristic will be as indicated by N'N in Fig. 5.

While I have shown and described my invention in considerable detail, I do not desire to be limited to the exact arrangements shown, but seek to cover in the appended claims all those modifications that fall within the time, spirit and scope of my invention.

What I claim as new and desire to secure by Letters Patent of the United States, is:

50 1. An electric circuit protective relay including two independent relatively movable cooperating members, means for actuating one member in accordance with the current of the circuit, means for biasing the other member against movement in one direction, and electromagnetic means for actuating said other member in said direction connected and arranged to operate in accordance with the difference between a voltage of the circuit and the circuit current.

55 2. An electric circuit protective relay including two independent relatively movable cooperating contacts, means for actuating one contact in accordance with the current of the circuit, means for biasing the other contact

against movement in one direction, and means for actuating said other contact in said direction in accordance with the difference between a voltage of the circuit and the current of the circuit.

60 3. An electric circuit protective relay including two independent relatively movable cooperating members, means for actuating one member in accordance with the current of the circuit, means for biasing the other member against movement in one direction, and means responsive to the current and voltage of the circuit operative with power flow in the circuit in a predetermined direction to actuate said other member in said one direction in accordance with the difference between a voltage of the circuit and the circuit current.

65 4. An electric circuit protective relay including two independent relatively rotatable cooperating members, means for rotating one member in accordance with the current of the circuit, means for biasing the other member against rotation in one direction; and means for rotating the other member in said direction comprising electromagnetic means arranged to exert a torque dependent on the difference between a voltage of the circuit and the current of the circuit.

70 5. An electric circuit protective relay including two independent relatively movable cooperating members, means for actuating one member in accordance with the current of the circuit, means for biasing the other member against movement in one direction, means for actuating said other member in said direction in accordance with the difference between a voltage of the circuit and the current of the circuit, and relay means operative on the occurrence of a fault in a predetermined portion of the circuit to eliminate the effect of the current in the actuating means of said other member.

75 6. In combination with an electric circuit and circuit interrupting means for one end of a section of the circuit, means for controlling said interrupting means including a relay having two relatively movable cooperating members, means for moving one member in accordance with the current of the circuit and means for moving the other member in accordance with the difference between a voltage of the circuit and the circuit current, and means operative on the occurrence of a fault outside of said section to eliminate the effect of the current in the actuating means of said other member.

80 7. In combination with an electric circuit and circuit interrupting means for one end of a section of the circuit, means for controlling said interrupting means including a relay having two relatively movable cooperating members, means operative on the occurrence of an over-current condition to move one member in accordance with the current,

means for biasing the other member against movement in one direction, and means including a distance relay operative on the occurrence of an over-current condition for actuating said other member in said direction in accordance with the difference between a voltage of the circuit and the current, and

means operative on the occurrence of a fault outside of said section to eliminate the effect of the current in the actuating means of said other member.

In witness whereof, I have hereunto set my hand this 28th day of November, 1927.

JOSEF BIERMANNS.
